OPEN-TOP MAILBOX WITH SLIDING
RECEPACLE ENGAGING COVER

Fred B. Gallaher, Wichita, Kans.

Application June 3, 1948, Serial No. 30,899

2 Claims. (Cl. 232—17)

1

My invention relates to an improvement in mail boxes.

An object of my invention is to provide a mail box that is neat in appearance, sturdy in construction, long lived, and one that is simple and easy to use.

A still further object of the invention is to provide a box of the kind mentioned in which there is a box within a box and the inner box is slideable up and down within the outer box so that any mail that may be in the mail box may be raised above the top of the outer box, whereby the mail may be easily taken hold of and removed from the mail box.

A still further object of the invention is to provide a mail box of the kind mentioned that has a hinged cover thereon and the cover may be raised by hand or if the inner box be raised, parts of the inner box will engage and raise the cover and lock it in its raised or open position.

A still further object of the invention is to provide a mail box of the kind mentioned in which the cover may be locked in a closed position, and the cover is provided with a mail slot through which mail may be entered into the box while the cover is locked in its closed position.

These and other objects of the invention will be more fully explained as this description progresses.

Now referring to the accompanying drawings in which similar numerals of reference designate the same parts throughout the several figures of the drawings:

Fig. 1 is a front view of the mail box.

Fig. 2 is a side view of the box, both sides being alike.

Fig. 3 is a top plan view of the box.

Fig. 4 is an enlarged detail perspective view of the cover locking device of the box.

Fig. 5 is a detail sectional view through the box and showing the box in a closed position, the view being as seen from the line V—V in Fig. 1 and looking in the direction of the arrows.

Fig. 6 is a view, the same as Fig. 5 except that the box is shown in an open position and the inner box is raised within the outer box.

Fig. 7 is a bottom plan view of the mail box.

Fig. 8 is a sectional view through the lower corner portion of the box, the view being as seen along line VIII—VIII in Fig. 1 and looking in the direction of the arrows.

Fig. 9 is a detail sectional view through the lower corner portion of the box, the view being as seen from the line IX—IX in Fig. 2 and looking in the direction of the arrows.

2

In the drawings the mail box is shown as having a front wall 10, side walls 11 and 12 and a rear wall 13. The rear edges of the side walls 11 and 12 are turned outwardly to form flange elements 14 and 15, which lay against the back wall 13 and are rigidly attached thereto by any suitable method such as welding, riveting or folding of the edges of the back wall 13 over the flanges 14 and 15 as desired. The upper edges 10 of the side walls 11 and 12 are cut so that they slope downwardly from back to front of the box. The box is provided with a cover 16. The cover 16 is hinged to the back wall by means of preferably, a piano type hinge 17. The front edge of the cover plate is turned downwardly as at 16a and the side edges 16b and 16c extend beyond the side walls 11 and 12 in the same plane with the cover plate 16. The cover plate 16 is provided with a letter hole or slot 18 which is partially covered by an inwardly and downwardly extending lip element 19.

The central portion of the upper end of the front wall 10 is provided with a channeled guide element 20, the channel portion of which faces the front plate 10 of the box and the end of the legs of the channel are turned outwardly as at 20a and are rigidly attached to the front box plate 10 by any suitable method, such as riveting or welding. Slidably carried in the channel 20 is a lock plate 21, the upper portion of which is provided with a cross head 22 that is wider than the plate 21 and is an integral part thereof and serves as a retainer for the plate 21 in the channel 20. The cross head 22 has a hole 23 therethrough for locking purposes as will later be described. The lower end of the lock plate 21 has a cross head formation 24 thereon that is wider than the lock plate 21 and is an integral part thereof and the lower edge of the cross head 24 is turned outwardly as at 25 to form a finger hold by which the lock plate 21 may be raised or lowered. The cover element 16 is provided with a slot 26 through which the cross head 22 may pass when the lock plate 21 is raised, whereupon the loop of a padlock may be passed through the hole 23 and the lock locked, whereupon the mail box is locked in a closed position.

The lower portion of the front wall 10 of the mail box is provided with an opening 27 for observation purposes as will later be described.

The box is provided with an exterior letter holder that consists of an inverted U-shaped element 28 that rests against the outer face of the front plate 10 of the mail box and is positioned around the opening 27. On the back side

of the front plate 10 and along the lower edge thereof is rigidly fixed looped holder elements 29 in which is held a rod 30 that extends, preferably to each of the side walls 11 and 12 of the box. Helical springs 31 and 32 are positioned, one around each end of the rod 30 with one end of each spring bearing against the back side of the front plate 10 as indicated at 31a. The outer end of each spring 31 and 32 project through slots 33 and 34 in the front plate 10 and connect, one with the lower end of each leg of the letter holder element 28 so as to yieldably hold the letter holder 28 against the front wall 10 of the box. The method of connecting the spring ends with the legs of the letter holder 28 may be any desired or suitable method, as shown in the drawings, the method of attachment is a longitudinally positioned hole in each leg end of the letter holder 28 in which is received the outer ends of the springs 31 and 32.

Within the foregoing described box is a second box that is slidably vertically therein. The second box has a front wall 35, two side walls 36 and 37, a rear wall 38 and a bottom 39 that slopes downwardly from front to rear. The upper edges of the front and side walls are positioned well towards the center of the outside box when the inner box is in its lowered position. However when the inner box is in its lowered position, the upper edges thereof extend well above the opening 27 in the front wall 10 of the outer box. The front wall 35 of the inner box is provided with an opening 40 that is of such size and is so positioned that when the inner box is in its lowered position the opening 40 therein and the opening 27 in the front wall 10 of the outer box will be in registry with each other.

The opening 40 in the front wall 35 of the inner box is covered with a transparent material such as glass or preferably transparent plastic material 41 which overlaps the edges of the wall 35 that bound the opening 40 and the transparent material 41 is held in position by flush rivets, not shown, which pass through the transparent plastic material 41 and the supporting metal of the front wall 35 of the inner box.

The inner box is provided with a finger lift element that comprises a loop portion 42 having an inwardly extending leg 43 that projects through the opening 27 at the bottom thereof and under the bottom 39 of the inner box and is rigidly attached thereto by any suitable means, such as welding or riveting so as to rigidly support the finger lift 42 outside the outer box whereby the inner box may be lifted or lowered within the outer box, and in this movement the finger lift 42 will travel up and down within the opening 27 in the front wall 10 of the outer box.

The rear wall 38 of the inner box is provided with an upwardly extending portion 38a which is merely an extension or continuation of the rear wall 38. The extension 38a extends upwardly to a point just beneath the cover 16 of the outer loop.

The box is provided with a guide strip 44 that is supported by the outer box and the upper portion of the rear wall 38a is slidably operable between the guide strip 44 and the rear wall 13 of the outer box so that as the inner box is raised the upper edge of the wall extension 38a will engage the cover 16 to raise it as will later be described. The use and operation of the box is as follows:

The mailman may insert mail into the box, either by lifting the cover 16 of the box and drop-

ping the mail into the box or if desired, he may place the mail in the box by inserting the mail through the opening 18 in the cover 16 of the box, whereupon the mail will fall into and rest on the bottom 39 of the inner box and will be visible through the transparent material 41.

Now to remove the mail from the box the inner box may be lifted by raising the finger hold 42, whereupon the inner box will be raised within the outer box and in this raising movement the upper edge of the rear wall extension 38a of the inner box will engage the under side of the cover 16 of the outer box and raise the cover 16 to a vertical position as the wall extension 38a progresses upwardly and as the wall extension 38a travels upwardly the upper edge thereof will be received behind the lip 19 and be guided through the opening 18 in the cover 16 of the box, whereupon the cover 16 of the box has been raised to its full open position and is now locked and held in its full open position by the rear wall extension 38a and by reason of its position through the cover 16. The inner box having been raised as above described, obviously would carry the mail in the box upwardly with the inner box and when the inner box is in its raised position the mail would project above and lean against the upper edge of the front wall 10 of the box, whereupon the mail may be easily taken hold of and removed from the box. The reason the mail will lean against the front wall 10 of the box is that the bottom 39 of the inner box slopes downwardly from the front to rear, therefore the bottom end of the mail supported by the bottom 39 will slide to the lower or rear edge of the bottom 39 which will automatically tip the upper end of the mail forward and to the front wall 10 of the box which places the mail in a position where it may be easily taken hold of for removal from the box.

The mail having been removed from the mail box as above described, the inner box may be lowered to its original position by moving the finger lift 42 downwardly to its original position, whereupon the back extension 38a will be withdrawn from the slot 18 and will be moved downwardly to its original position, whereupon the cover 16 will fall to its original closed position. The cover having moved to its closed position may be locked closed if desired, by raising the lock plate 21-22 upwardly until the portion 22 thereof passes through the slot 26 and extends above the upper surface of the cover 16, whereupon the loop portion of a padlock may be passed through the hole 23 and the lock closed or locked, whereupon the mail box is locked in a closed position and mail therein cannot be removed therefrom until the padlock is unlocked and removed from the box.

Now while my improved mail box as shown in the drawings and described in the foregoing specification is probably the preferred form of the invention, it is to be understood that such modifications of the invention may be employed as lie within the scope of the appended claims without departing from the spirit and intention of the invention. Now having fully shown and described my invention, what I claim is:

1. In a mail box of the kind described comprising in combination, an outer casing and a receptacle carried and being vertically slidably therein, said casing and receptacle having open tops, a cover for said casing and receptacle hingedly attached to the upper edge portion of

the rear wall of said casing and having a mail receiving opening in the central portion thereof, the lower portion of the front wall of said casing having an opening therein, means carried by said receptacle projecting through the casing opening for raising and lowering the receptacle in said casing opening for raising and lowering the receptacle in said casing, and means carried by the receptacle for entering and passing through the said mail receiving opening for stabilizing the said cover when in an open position.

2. In a mail box of the kind described and defined in claim 1, said stabilizing means comprising an upward extension of the rear wall of the

receptacle, narrower than the width of said receptacle.

FRED B. GALLAHER.
